FEELER DEVICE FOR LOOMS

Juan Picañol Camps, Sabadell, Spain

Application August 20, 1932, Serial No. 629,668
In Switzerland June 21, 1932

3 Claims. (Cl. 139—273)

This invention refers to a new feeler device for automatically changing the cop.

There are a great many kinds of apparatus constituting feelers for automatically changing the cop, and up to the present the electric devices have given the best results. However, when high speeds are reached these suffer from the defect implied in the want of adherence between the feeler mechanism and the cop of the loom, caused 5 by the horizontal movement and the consequent inertia produced by the abrupt stoppage on the part of the shuttle due to the movement of the loom.

This inconvenience is completely eliminated by 10 means of the device which is the object of this patent.

In the drawings, which are an integral part of this specification, are shown:—

Fig. 1 a side view of the mechanism
20 Fig. 2 a plan of the mechanism and its corresponding derivations.

Referring to the drawings in more detail, these show 1 fibre stop, 2 bearing, 3 springs, 4 loom guide, 5 bearing, 6 shuttle, 7 loom slay, 8 cop, 9 picker, 10 metal cover on the cop, 11 axis of the spring, 12 fibre washer, 13 terminal, 14 oscillating piece of the loom, 15 small lever, 16 bobbin, 17 revolving lever of the automatic change mechanism, 18 axis of the mechanism which produces 25 the automatic change, 19 union of the two terminals, 20 electric motor, 21 small contact lever, 30 22 transformer, 23 mass contact.

The device works as follows:—By means of the 35 loom, when it is normally working, as indicated by the arrow in Fig. 1, the metal covers of the cops come into contact with the springs 3. These springs in contact with their piece 11, and each 40 of them provided with terminals 13, are supplied with an electric current produced by the motor 20 which goes through the transformer 22 and the contact lever 21 to the terminals 19.

It will be understood, therefore, that when the 45 two springs 3 are in contact with the metal cover of the cop 10 an electric current is produced which is communicated to the bobbin 16, and this in its turn manipulates the small lever 15 coming in contact with the oscillating piece of the loom 14 which results in a movement in the direction of the arrow this movement being transformed 50 into an oscillation of the small lever 17 which it

passes on to its shaft 18. In this way the mechanism for the automatic changing of the cop is able to function.

By the foregoing it will be seen that the automatic changing of the cop is effected by means of 5 a perfect adherence of the feeler to the cop, thus avoiding completely the abrupt stoppage which takes place in other feelers due to their own inertia.

In this device there is produced at the precise 10 moment of contact the electric circuit necessary to the bobbin so as to move the small lever and this latter in its turn effects the instantaneous change. In this way, due to the small surface of 15 a steel wire, however small may be the parts exposed the cop when empty leaves little residue of thread.

I claim:

1. A loom weft-feeler device, comprising in combination with the lay, the breast beam of the 20 loom and the metal sleeve of the cop bobbin, a support of insulating material carried by said breast beam and adapted to be moved back by the lay in its movement towards said breast beam, two spring wires spirally wound about and fixed 25 at one end to said support, an arm formed at the other end of each spring adapted to be pressed into contact with the metal sleeve of the cop bobbin by the spirally wound portion of the wires, and an electric circuit connected to said arms and 30 adapted to be closed by the contacting of said arms against said metal sleeve.

2. In a feeler device as specified in claim 1, a disc of insulated material mounted on the support between the spirally wound portions of the two 35 spring wires.

3. In a feeler device as specified in claim 1, a cop changing mechanism adapted to be actuated by the closing of the electric circuit and comprising a rocking shaft, a bracket mounted on said 40 shaft, an electro-magnet carried by said bracket, and connected up in said circuit, said magnet adapted to be excited by the closing of said circuit, a catch lever oscillatable on said shaft and adapted to be attracted by the excitation of said 45 magnet, and a bell crank lever in the path of movement of said catch lever and adapted to operate with same to actuate the cop changing device.
